SHOE AND THE METHOD OF MAKING SAME

Isaac F. Damon, Belmont, Mass., assignor to
Compo Shoe Machinery Corporation, New
York, N. Y., a corporation of Delaware

Application January 4, 1934, Serial No. 705,170

9 Claims. (Cl. 12—142)

This invention aims to provide functionally and structurally improved articles, primarily intended for use in connection with the manufacture of shoes, and also aims to teach a novel method of manufacture in connection with the production of shoes.

It is an object of the invention to provide a sole of novel construction, and by means of which the methods of manufacturing shoes may be greatly improved.

A further object is that of providing an inset or filler piece in connection with the use of insoles and by means of which the resultant product will be greatly improved.

A still further object is that of teaching a method of manufacturing shoes, which method will preferably employ soles and filler pieces as afore noted, the practice of such method resulting in the expeditious manufacture of shoes having improved characteristics.

Moreover, by means of the present invention, there are provided soles and insets which may be economically manufactured in large quantities, and the method as taught by the present invention will not require the services of an especially skilled workman.

With these and other objects in mind, reference is had to the attached sheet of drawings illustrating practical embodiments of the invention, and in which:

Fig. 1 is a perspective view of an inner sole;
Fig. 2 is a transverse sectional view taken along the lines 2—2 and in the direction of the arrows as indicated in Fig. 1;

Fig. 3 is a perspective view of a shoe-upper and showing the same in association with a sole of the type illustrated in Fig. 1, during the lasting operation;

Fig. 4 is a view similar to Fig. 3, but showing the shoe after the same has been subjected to a further step of manufacture;

Fig. 5 is a transverse sectional view of the shoe and sole as illustrated in Fig. 4, with an outsole added;

Fig. 6 is a sectional and perspective view thereof; and

Fig. 7 is a view similar to Fig. 5, but showing a slightly different form of construction from that illustrated in the preceding figure.

In these views, the numeral 10 indicates an inner sole which, for example, at the time of manufacture is slit or scored as is indicated at 11, so that a central portion 12 may be removed, it being noted, however, that said central portion 12 is maintained against accidental displacement

by leaving uncut or unscored zones 13, and deliberate destruction of which is, of course, necessary to effect removal of the portion 12.

In forming the slit or score 11, care is preferably taken so that the edges shall be beveled as at 14 in Fig. 2. It is obvious that this beveling might be followed to any desired extent, and might readily be conducted at the time the sole is stamped or cut out.

In any event, the inner sole 10 and the upper 15 may be applied in the usual manner to the last 16, and the lasting operation is conducted in any suitable manner, as, for example, by cementing the lasting allowance 17 to the margins 18 of the insole. During this operation, and incident to 15 the central portion 12, the insole will offer sufficient resistance to buckling so that no difficulties may be apprehended. Thereafter, by simply cutting through the zones 13, the central portion 20 may be removed.

The operator may now apply to the insole the filler piece 19, which piece should be of a thickness such that it will extend from the plane of the inner face of the sole 10 to the plane of the outer face of the lasting allowance. While, for the 25 purpose of illustration, the filler piece has been shown as having a somewhat reduced area, it will of course, be understood that preferably the area thereof should be substantially equal to the area between the inner edges of the lasting al- 30 lowance so that substantially continuous surfaces are provided.

Of course, before the application of the filler piece 19, but after the removal of the central portion 12, the operator may modify the edges of 35 the central opening as may seem most desirable. Such modification may take the form of beveling to a greater extent than has been done prior to the application of the inner sole to the upper. Also, as shown, in Fig. 7, the filler piece need not 40 necessarily have those edges which contact the edges of the central sole beveled, but instead a shoulder 20 may be provided at this point, the depth of the shoulder being such that the inner face of the inset or filler piece will lie in the inner plane of the insole, while the outer face of such inset will extend into the plane of the outer face of the lasting allowance.

A permanent coupling of the parts may be secured by cementing, and while the inner sole 50 may be formed of any desirable material, it is preferred that it be provided of composition. Likewise, while lasting allowance may be secured to the sole according to the method of manufacture which is being followed, it is preferred that

cementing be resorted to to assure a permanent union between these parts. In many respects it is preferable that slitting, as indicated at 11, be resorted to, but it is obvious that, regardless of whether a composition or other sole is being utilized, a line of weakening might be furnished, as, for example, by a crushing action, which would substantially remove said portion but nevertheless leave in existence a thin layer of material, precluding accidental detachment of such portion. Under the latter circumstances the unsevered areas 13 might be utilized or entirely dispensed with, in that the operator could very easily complete the removal of the central portion. In certain instances, and especially where scoring is utilized, these unsevered areas might again be dispensed with.

From the foregoing it is obvious that a sole is provided and a method taught which will permit of adequate support being furnished during the lasting operation and by means of which, after such operation has been completed, the rigidifying portion may be removed with facility and replaced by a filler piece or inset which will assure the incorporation of maximum flexibility and comfort in the resulting shoe. The outer faces of the lasting allowance and inset might be skived, so that the outer sole might readily be cemented thereto, it being, however, immaterial—in so far as the present invention is concerned—whether cementing, stitching, or other forms of attachment are employed.

It will be noted, particularly in Figs. 5 and 7, that by virtue of the thickened insert in the inner sole the latter has a centrally elevated portion or land which projects outwardly from the bottom face of the lasted upper. The boundary of this landed portion approximately coincides with the inner boundary of the inner sole lasting allowance, and in the complete lasted upper assembly there is a substantially even surface extending from side to side of the shoe which is adapted to mate firmly and snugly with an outer sole, which latter may be readily manufactured in a flat condition with a minimum number of preforming steps.

From the foregoing, it will be obvious that, among others, the several objects of the invention as specifically afore noted, are achieved. It will be appreciated that numerous changes in construction might be resorted to, and that the steps and the method might be varied in many respects without departing from the spirit of the invention as defined by the claims.

Having thus described the invention, what is claimed as new and desired to be protected by Letters Patent is:

1. A shoe comprising an insole having an apertured central forepart portion surrounded by a rand, a filler piece having thin marginal portions overlying the outer face of the inner portion of said rand and having a thicker central portion occupying said aperture with its inner face flush with the inner face of said rand, an upper lasted to said insole, and an outsole affixed to said upper with its central forepart portion directly engaging and resting against said filler piece, said filler piece being of sufficient thickness to compensate for the thickness of the lasting allowance of said upper and to form, with said rand, upper and outsole, a sole portion of uniform thickness on the bottom of the shoe.

2. A shoe comprising an insole having an apertured central forepart portion surrounded by a rand, a filler piece having thin marginal por-

tions overlying the outer face of the inner portion of said rand and having a thicker central portion occupying said aperture with its inner face flush with the inner face of said rand, an upper lasted to said insole with the outer surface of its forepart lasting allowance merging smoothly with the outer surface of said filler piece, and an outsole attached to the thus formed shoe bottom with its flesh side engaging and resting against said lasting allowance and filler piece, said filler piece being of sufficient thickness to compensate for the thickness of the lasting allowance of said upper and to form, with said rand, upper and outsole, a sole portion of uniform thickness on the bottom of the shoe.

3. A shoe comprising an insole having an aperture in its central forepart portion surrounded by a rand, a filler piece having thin marginal portions overlying the outer face of the inner portion of said rand and having a thicker central portion occupying said aperture with its inner face flush with the inner face of said rand, an upper lasted to the outer margin of said insole with the overturned lasting allowance at its forepart flush with the outer surface of said filler piece, and an outsole attached to the thus formed shoe bottom with its flesh side engaging and resting against said lasting allowance and filler piece, said filler piece being of a thickness sufficient to compensate for said lasted upper and to prevent the portion of said outsole adjacent said insole aperture from being relatively depressed.

4. A shoe comprising an insole having an aperture in its central forepart portion surrounded by a rand, an upper lasted to the outer marginal portion of said insole with the edge of its overturned lasting allowance at the forepart located outwardly from said aperture, a filler piece having thin marginal portions overlying the exposed inner margin of said rand inwardly of the edge of said lasting allowance, and having a thicker central portion occupying said aperture with its inner face flush with the inner face of said rand, the outer face of said filler piece being flush with the outer face of said overturned lasting allowance, and an outsole attached to the thus formed shoe bottom with its flesh side engaging and resting against said lasting allowance and filler piece.

5. In a shoe, an insole having an aperture through its forepart surrounded by an inwardly tapered rand, and a filler piece having a feathered margin overlying the inner portion of said rand, the inner face of said filler piece being flush with the inner face of said rand and the outer face of said filler piece being elevated above the outer face of said rand a distance substantially equal to the thickness of the upper lasting allowance of said shoe.

6. A method of making shoes, which comprises, providing an insole having an aperture through its forepart surrounded by an inwardly tapered rand, and an upper having an overturned lasting allowance lasted to said insole, providing a feathered filler piece of sufficient thickness to compensate for the thickness of said lasting allowance at the forepart and of a size to cover said aperture and the adjacent inner margin of said rand, attaching the feathered margin of said filler piece over said inner rand margin with the inner face of said filler piece flush with the inner face of said rand and with the outer face of said filler piece forming a smoothly continuing surface with the outer face of the overturned last-

ing allowance of said upper, providing an outsole with its flesh side fitting snugly against said smoothly continuing lasting allowance and filler piece surfaces, and attaching said outsole to the 5 shoe bottom with its flesh side in such fitted position.

7. A shoe comprising an insole having an aperture in its central forepart portion surrounded by a rand, an upper lasted to the outer marginal 10 portion of said insole with the edge of its overturned lasting allowance at the forepart located outwardly from such aperture, a filler piece having its marginal portions overlying the exposed inner margin of said rand and having its central 15 portion spanning said aperture, the outer face of said filler piece being flush with the outer face of said overturned lasting allowance, and an outsole attached to the thus formed shoe bottom with its flesh side engaging and resting against 20 said lasting allowance and filler piece.

8. A method of making shoes which comprises lasting a shoe having a skeleton insole having an aperture through its forepart surrounded by an inwardly tapered rand, and an upper having 25 an overturned lasting allowance lasted to said insole without covering the inner portion of the rand, applying a filler piece of a size to cover said aperture and the exposed portion of said rand to the shoe bottom with its central por-

tion supported by the last through said aperture, said filler piece being of a thickness to compensate for the thickness of said lasting allowance at the forepart of the shoe, and attaching an outsole to said shoe bottom with its marginal 5 forepart portions resting against said lasting allowance and with its central forepart portion supported by said filler piece.

9. A shoe comprising a skeleton insole having an aperture in its central forepart portion surrounded by an inwardly tapered rand, an upper lasted to said insole with the edge of its overturned lasting allowance at the forepart located outwardly from such aperture, a filler piece having its marginal portions overlying the exposed 10 inner margin of said rand and having its central portion spanning said aperture, the inner face of said filler piece being flush with the inner surface of said rand, said filler piece being of sufficient thickness to compensate for the thickness 15 of said overturned lasting allowance at the forepart of the shoe and having its outer surface merging smoothly with the outer surfaces of such lasting allowance, and an outsole attached to the thus formed shoe bottom with its flesh side 20 engaging and resting against said lasting allowance and filler piece.
